UNITED STATES PATENT OFFICE

2,568,801

POLARITY REVERSER

George E. G. Graham, Streatham, London, England, assignor to Cinema-Television Limited, London, England, a corporation of England

Application October 28, 1947, Serial No. 782,551
In Great Britain May 15, 1947

4 Claims. (Cl. 250—27)

1

This invention relates to improvements in methods of and apparatus for controlling electrical signals and is especially concerned with new and improved means for selectively controlling the polarity of such signals.

For certain purposes it is desirable to be able to control the polarity of electrical signals, that is, to be able to arrange that signals derived from one part of a circuit shall be applied to another part of the circuit in either positive or negative polarity, the control of the polarity being effected by means of a substantially inertia-free device. Means for effecting such control have hitherto been relatively complex, consisting in general of two signal channels rendered alternatively operative, one of said channels being arranged to reverse the polarity of signals applied thereto, while the other channel passes signals without changing their polarity. Arrangements of this type suffer from the disadvantages of complexity and signal distortion due to the imperfections of the polarity inverter and the excessive stray capacities introduced into the circuit.

The present invention seeks to overcome the aforesaid disadvantages by making use of a valve of the type comprising a cathode, an anode, from which signals are to be derived, a first control electrode adapted to control the total emission from said cathode and at least another control electrode adapted to produce a variation of current within said valve such that the slope of the characteristic of the anode current versus first control electrode potential is thereby reversed.

According to the present invention there is provided a method of selectively controlling the polarity of electrical signals which method consists in applying said signals to the first control electrode of a valve of the type defined, deriving controlled signals across an impedance connected in the anode circuit of said valve and varying the potential of a second control electrode of said valve so as to cause the derived signals to have the desired polarity.

Equally according to the present invention there is provided a circuit for selectively controlling the polarity of electrical signals comprising a valve of the type defined to a first control electrode of which signals are applied and from the anode of which controlled signals are derived and means for varying the potential of a second control electrode of said valve so as to cause the derived signals to have the desired polarity.

In order that the present invention may be more fully described, reference is now made to the accompanying drawings of which

Figure 1 is a diagram illustrating certain voltage-current relationships within a valve of the type defined,

Figure 2 is a circuit diagram of one embodiment

2

ment of apparatus according to the invention, and

Figure 3 is a series of waveforms illustrative of the operation of the circuit shown in Figure 2.

Referring now to Figure 1, the curve marked A illustrates the shape of the characteristic of anode current versus signal-grid potential of one type of screen grid valve when the potential on the anode of the valve is approximately 90 volts and that on the screen grid is approximately 130 volts. It will be seen that the slope of curve A is negative, that is, the anode current becomes progressively smaller as the signal-grid potential becomes progressively more positive. This phenomenon is well known, and is due to the fact that each electron incident upon the anode causes the ejection from the anode of one or more other electrons, which are drawn towards and collected by the screen grid. The number of electrons collected by the screen grid is determined by the high screen potential relative to the anode. Thus the total space current flowing to the anode is of negative polarity, that is, more electrons leave the anode than arrive at it. This is known as "secondary emission."

The curve B, on the other hand, illustrates the anode current versus signal-grid potential characteristic of the same type of valve when the anode potential is still approximately 90 volts and the screen-grid potential is reduced to substantially the same value. It will be seen that in this case the slope of the curve is positive, that is, changes in grid potential in a positive direction result in increases in anode current.

If, therefore, an input signal be applied to the signal-grid of a valve in the condition represented by curve A, the output signal appearing on its anode will have the same polarity as the applied signal, while if the valve be in the condition represented by curve B, the output signal will be of reversed polarity. As the difference between conditions A and B is that of a difference in the screen-grid potential, it will be seen that the valve may rapidly be changed from one condition to the other by applying a suitable change in potential to the screen grid.

Figure 2 illustrates an embodiment of a circuit according to the present invention. A screen grid valve 1 has its cathode connected to ground through a biasing resistance 13 and its anode connected to a source of suitable energizing potential B+ through a load resistance 2. Output signals which appear at the anode of the valve 1 are available to a utilization circuit over blocking condenser 3 and across output terminals 4.

Input signals are applied to the circuit across terminals 5 from which they are fed to the signal grid of valve 1 via condenser 6 and re-

turned to ground through grid resistances 7 and 8 in series.

The screen grid of the valve is connected to a source of energizing potential, for example to the source, B+ through an appropriate dropping resistance 11 having a value suitable for reducing the B+ voltage to the normal screen grid working voltage.

Control voltages are applied across terminals 9 from which they are fed to the screen grid of valve 1 over blocking condenser 10. It is customary in most applications of screen grid tubes to ground the screen grid as to varying voltages by connecting it to ground over a condenser thus by-passing the screen power supply including the direct current dropping resistor, with a low impedance element, i. e. an element having a low value of capacitative reactance. In the present application the screen grid may be suitably stabilized by employing a source of control voltages which has a low internal or "output" impedance.

For reasons stated below it is desirable also to apply the control voltages to the signal grid and to apply them there in reduced amplitude. For this purpose the control signals are also applied across a voltage divider comprising resistors 12 and 8 and the portion thereof which appears across resistor 8 is applied to the signal grid over the resistor 7. Since Figure 2 is diagrammatic, well known circuit elements, such as the cathode heater and its supply circuit, are omitted. It is obvious, however, that in constructing actual embodiments of this invention these elements must be included and may be arranged in accordance with general practice, for example, for most embodiments it will be necessary to use a blocking condenser between the lower end of resistances 11 and the upper end of resistance 12.

The operation of the circuit will now be described with reference also to Figure 3, which illustrates the voltage waveforms appearing at different parts of the circuit of Figure 2 under certain conditions. Waveform a is that of the control voltages applied across terminals 9 and thence to the screen grid of the valve 1, waveform b exemplifies the wave form of input signals applied to terminals 5 and thence to the signal grid of the valve, and waveform c is that of the corresponding output voltages appearing at terminals 4 under the operating conditions further discussed below.

The steady potential applied to the screen grid via the resistance 11 is such that when the signal shown at a of Figure 3 is applied the valve is made to alternate between the conditions illustrated by curves A and B of Figure 1, that is the output signals will be of the same and of reversed polarity with respect to the input signal during alternate half-cycles of the waveform of Figure 3a. With the waveform of Figure 3b applied to the signal grid, therefore, the output will be of the form shown in Figure 3c, alternate pulses being of opposite polarity.

There is an incidental effect which should be noted, namely that the application of the control voltages to the screen grid will alternately lower and raise the anode current somewhat and will produce at the anode of the valve a spurious signal whose wave form corresponds to wave form a of Figure 3. This effect is counteracted by also applying the control voltages to the signal grid of the valve 1 in a reduced amplitude which is appropriately controlled to tend to produce

an equal and opposite spurious signal at the anode so that compensation is obtained, i. e., the two spurious anode signals exactly cancel each other. The control voltages applied to the screen grid is also applied across resistances 12 and 8 in series, so that only a fraction thereof appears across resistance 8. This resistance is connected to the signal grid over resistor 7 and therefore this fraction of the signal is applied to the signal grid where it produces an opposing effect at the anode. More specifically: as each positive-going square wave of the control voltage applied to the screen grid causes increased secondary emissions from the anode thus causing a decrease in anode current and a spurious increase in anode potential, a corresponding but smaller, positive square wave will be applied to the signal grid to appropriately increase anode current and decrease anode potential so that there is no appreciable over-all change in anode potential and vice-versa. By suitable choice of the values of resistances 12 and 8 the compensation may be made substantially complete. The resistance 13 is chosen such as to give an effective grid bias of suitable amount. It is not provided with a bypass condenser, as the negative feedback obtained by the omission of this component has a valuable straightening effect on the effective characteristic of the valve.

It will be understood that the invention is not limited to the specific embodiment described with reference to Figures 2 and 3 which is capable of many modifications without departing from the scope of the invention.

What is claimed is:

1. Apparatus for controlling the polarity of electrical signals comprising a four element electron discharge device having a cathode, a signal grid, a screen grid and anode, means for applying direct potential to the screen grid and to the anode, means for applying the signals to the signal grid, means for applying control voltages to the screen grid for alternately reversing the direction of the current to the anode so that the polarity of the signals appearing at the anode is also reversed, a voltage divider circuit, means for applying the control voltages to the divider circuit, means for applying a portion of the control voltages from the divider circuit to the said signal grid, and means for taking the controlled electrical signals from the anode.

2. Apparatus for controlling the polarity of signals as in claim 1, in which the control voltages comprise square waves.

3. An apparatus as in claim 1, and in which the potential of the screen grid alternately rises above and falls below the potential of the anode so that the secondary emission from the anode is alternately encouraged and prevented.

4. An apparatus as in claim 3, and in which the direct potentials of the screen grid and the anode have the same value and the control voltages comprise square waves of equal amplitude.
